CLAIM

The ornamental design for a jewelry stone, as shown and described.

DESCRIPTION

FIG. 1 is a top plan view showing my new design;
FIG. 2 is a bottom plan view thereof;
FIG. 3 is a front elevation view thereof, where the front side, the rear side, the left side and the right side are all mirror images of each other;
FIG. 4 is another side elevation view thereof, taken from a 45 degree offset from the view of FIG. 3;
FIG. 5 is top and side perspective view thereof; and,
FIG. 6 is a bottom and side perspective view thereof.
